UNITED STATES PATENT OFFICE.

WILLIAM D. THOMAS, OF PITTSBURG, PENNSYLVANIA, ASSIGNOR TO HIMSELF, ROBERT J. PEEL, AND THOMAS B. ATTERBURY, ALL OF SAME PLACE.

FLUID-PRESSURE REGULATOR AND CUT-OFF.

SPECIFICATION forming part of Letters Patent No. 365,712, dated June 28, 1887.

Application filed March 18, 1887. Serial No. 231,415. (No model.)

To all whom it may concern:

Be it known that I, WILLIAM D. THOMAS, of Pittsburg, in the county of Allegheny and State of Pennsylvania, have invented a new and useful Improvement in Fluid-Pressure Regulators and Cut-Offs; and I do hereby declare the following to be a full, clear, and exact description thereof, reference being had to the accompanying drawings, forming part of this specification, in which—

Figure 1 is a side view of the regulator, the side of the box or chamber being removed to show the interior mechanism. Fig. 2 is a vertical longitudinal section through the regulator-chamber and the cylinders 3 and 13.

Like symbols of reference indicate like parts in each.

In the drawings, 2 represents the box or case of the regulator.

3 is the gas-adit pipe, and 4^a is the exit-pipe. In the pipe 3 is arranged a valve having two faces, 4 and 5, which are screwed to a single stem, 6, and seat in opposite directions on their seats 7. The valve-faces 4 and 5 are screwed to the stem 6, and are therefore adjustable to vary the distance between them. When properly adjusted, they are locked by nuts *b*. The stem 6 is connected at its upper end to a lever, 8, which is fulcrumed at a point, 9, and is weighted at 10. The free end of the lever has depending from it a rod, 11, which is fixed to a piston or plunger, 12. The piston or plunger works in a cylinder, 13, which communicates with the case 2.

14 is a rod extending from the piston to the outside of the cylinder 13, and 15 is a vent-pipe, which leads from the cylinder to the outer air.

16 is a small by-pass pipe, which leads from the adit-pipe 3, back of the valves 4 and 5, into the chamber 2. It is provided with a cock, 17.

Fig. 2 shows the regulator working, with gas flowing past the valves into the case and through the pipe 4^a. The valves are so held by gas-pressure on the piston 12. When the pressure in the case 2 increases, it forces the piston 12 down in the cylinder 13, thus depressing the unweighted end of lever 8 and moving the valve-face 4 nearer to its seat, so as to diminish the gas-flow. If the pressure should fall, the weight 10 drops and raises the valve 4 to admit more gas, and in this

way an equilibrium of pressure, depending for amount on the position and gravity of the weight 10, is continually maintained. If the pressure in the supply-pipe 3 should cease altogether, or should fall below the pressure at which the regulator is set, the weight drops and raises the valve 5 to its seat, thus cutting off the gas-flow.

The regulator may be started into operation either by pulling down the rod 14, so as to push the valve-face 5 from its seat, or it may be started by opening the cock 17. This lets a small supply of gas into the case 2 and depresses the piston 12, so as to unseat the valve 5; but if there be any considerable leak, or if any burner-valves be open in the service-pipe in advance of the regulator, the gas will escape without operating the piston 12, and so will not affect the regulator until the outlets be shut. This is an advantage, because it indicates the condition of the pipes and prevents the full gas-supply being turned on until the valves have all been shut.

I am aware that double-faced valves in a regulator are not new, nor is it new to suspend a double-faced valve vertically from a lever and to work the lever with a diaphragm. I therefore do not claim these. My invention consists in the combination of the double-faced valve, the lever arranged in the case 2, and the piston 12, connected with the lever, and having the rod 14 projecting from the cylinder 13, wherein the lever works.

I therefore claim—

In a fluid-pressure regulator, the combination, with the case or box 2, of the exit and adit pipes, a double-faced valve controlling the adit-pipe, a cylinder, 13, communicating with the case or box 2, a piston, 12, in the cylinder, and a lever, 8, arranged inside the said case or box and connected with the piston and with the valve, whereby increase of gas-pressure in the case or box moves the piston, and through the lever 8 moves the valve and the stem 14, connected with the piston and projecting without the cylinder, substantially as and for the purposes described.

In testimony whereof I have hereunto set my hand this 10th day of March, A. D. 1887.

WILLIAM D. THOMAS.
